Specification for Design.

Patented May 31, 1921.

Application filed November 10, 1920. Serial No. 423,193. Term of patent 14 years.

To all whom it may concern:

Be it known that I, EDWARD L. CAMPBELL, a citizen of the United States of America, residing at Winona, in the county of Winona, State of Minnesota, have invented a new, original, and ornamental Design for a Vehicle Tire or Casing, of which the following is a specification, reference being had to the accompanying drawings, forming part thereof.

In the drawings:—

Figure 1 is a side elevation of a section of a tire or casing showing my new design.

Fig. 2 is a plan view of the same.

Fig. 3 is a cross section on the line 3—3, Fig. 2.

I claim:

The ornamental design for a vehicle tire or casing, substantially as shown.

EDWARD L. CAMPBELL.
